(57) **CLAIM**

The ornamental design for a thin coaxial multi-wire unit with a ground bar, as shown and described.

DESCRIPTION

FIG. 1 is a front elevational view of a thin coaxial multi-wire unit with a ground bar;

FIG. 2 is a rear elevational view thereof;

FIG. 3 is a right side elevational view thereof;

FIG. 4 is an enlarged cross-sectional view thereof along the line 4—4 of FIG. 1;

FIG. 5 is a top plan view thereof;

FIG. 6 is a bottom plan view thereof; and,

FIG. 7 is a perspective view of the front and right side thereof.

A left side elevational view of the electrical connector is omitted because it is presented symmetrical to the right side elevational view of FIG. 3.

In the plan view, the unit actually has a lateral width of 2 cm and a longitudinal length of 30 cm or 60 cm. However, it is shown with an interrupted longitudinal length by dash-and-dot lines. A specific length for the unit forms no part of the claimed design.
